(57) **CLAIM**

The ornamental design for a fish lure, as shown and described.

DESCRIPTION

FIG. 1 is a front, top and right perspective view of a fish lure showing my new design;

FIG. 2 is a right side elevational view of the fish lure of FIG. 1, the left side elevational view being a mirror image thereof;

FIG. 3 is a top plan view of the fish lure of FIG. 1;
FIG. 4 is a bottom plan view of the fish lure of FIG. 1;
FIG. 5 is a front elevational view of the fish lure of FIG. 1; and,

FIG. 6 is a rear elevational view of the fish lure of FIG. 1. The broken lines depict unclaimed environmental subject matter and form no part of the claimed design.
